UNITED STATES PATENT OFFICE.

JOSEPH A. AMORI, OF SAN JOSE, CALIFORNIA.

AUXILIARY AIR SUPPLY FOR FUEL VAPORIZERS.

Application filed May 18, 1922. Serial No. 560,857.

To all whom it may concern:

Be it known that I, JOSEPH A. AMORI, a subject of the King of Italy, and resident of San Jose, in the county of Santa Clara and State of California, have invented certain new and useful Improvements in Auxiliary Air Supplies for Fuel Vaporizers, of which the following is a specification.

My invention relates particularly to the auxiliary air supply for the vaporized fuel of internal combustion engines.

It is the object of my invention to provide an air supply of the character indicated that is automatically regulated by the suction of the engine supplying a proper amount of auxiliary air under any and all engine loads and speeds.

Figure 1 is a sectional view of a device embodying my invention mounted upon the manifold of an internal combustion engine showing the auxiliary air port cut off.

Figure 2 is a cross-section of the auxiliary air port showing the same in the open position, parts being broken away.

Figure 3 is a cross-section of the same showing the auxiliary air port closed, parts being broken away.

Figure 4 is a section on line 4—4 of Figure 2, parts being broken away.

Referring more particularly to the drawing, 1 indicates a portion of an internal combustion engine, and 2 a carburetor connected thereto by means of manifold 3 and intake pipe 4.

In the embodiment of my invention herein disclosed, the manifold intake pipe 4 is provided with two ports 5 and 6. To port 6 is connected a pipe 7 communicating with a chamber 8 provided with a recess arranged at right angles to pipe 7.

Connected to port 5 is a pipe T 10 the opposite openings of which are indicated at 11 and 12 respectively. Chamber 8 and opening 12 of T 10 are connected by a pipe 13, and opening 11 of T 10 is fitted with a pipe section 14 fitted with a stop 15. The two pipe sections 13 and 14 fit into T 10 to form an annular chamber 16 therein between the ends of said pipe sections and communicat-

ing with port 5 through T 10 at all times. Slidably mounted in pipe sections 13 and 14 is a tube 17 closed at the end 18 directed toward chamber 8 but open at its opposite end as at 19 and provided with a port at 20. At 21 is a spring inserted in recess 9 of chamber 8 and engaging the closed end 18 of tube 17.

When the device is assembled as above described spring 21 normally holds tube 17 against stop 15 so that port 20 is closed off by pipe section 14. The engine being put into operation the suction through pipe 4 tends to produce a vacuum in chamber 8 thereby moving tube 17 lengthwise in pipe 13, in the direction of chamber 8 and bringing port 20 more or less into communication with chamber 16 and port 5, the degree of suction in chamber 8 automatically positioning port 20 and regulating the amount of auxiliary air admitted through the open end of tube 17 and pipe 14.

If the engine is running at rather high speed but a somewhat light load then the full amount of auxiliary air is admitted. If, however, the load should be greatly increased as by ascending a hill, a much richer fuel mixture is desired. This richer mixture is instantly and automatically supplied because the increased suction due to the increased load moves tube 17 still further along in pipes 13—14 until port 20 is closed off by pipe 13 and the flow of auxiliary air is cut off as shown in Figure 3. A decrease in engine load automatically moves port 20 back into communication with chamber 16 and port 5, and a proportionately leaner mixture is provided.

It may now be seen from the foregoing disclosure that I have provided a device whereby the vaporized fuel passing through the engine manifold may be reduced or increased in richness as the work performed by the engine demands, and this result is obtained automatically. A much finer adjustment of air to fuel is obtained in an automatic adjustment of this nature than can be obtained through manual adjustments as the movement of tube 17 is instantaneous with any variation in engine suction.

It is to be understood, of course, that while I have herein shown and described one particular embodiment of my invention that changes in form, proportion, construction and method of operation may be made within the scope of the appended claim.

I claim:—

In combination with the suction tube of the manifold of an internal combustion engine, having spaced ports formed therein, a pipe section connected to one port having a chamber formed therein and a recess extending at right angles thereto and communicating with said chamber, a pipe section connected

to the other port and provided with a chamber in axial alignment with said first mentioned chamber, a pipe section connecting said chambers, a pipe section communicating with said second chamber in axial alignment therewith and having a stop in its outer end, a tube closed at its inner end slidably mounted in said last named pipe sections and passing through said last

named chamber, a spring inserted in a recess in said first named chamber and engaging said tube and normally holding the same in engagement with said stop, and a port formed in said tube and movable into and out of communication with said second chamber.

JOSEPH A. AMORI.
